UNITED STATES PATENT OFFICE.

WILLIAM McAUSLAND, OF TAUNTON, MASSACHUSETTS, ASSIGNOR TO THE REED & BARTON CORPORATION.

INSULATING HANDLE CONNECTION.

SPECIFICATION forming part of Letters Patent No. 605,448, dated June 7, 1898.

Application filed April 30, 1897. Serial No. 634,621. (No model.)

To all whom it may concern:

Be it known that I, WILLIAM McAUSLAND, a citizen of the United States, residing at Taunton, in the county of Bristol and Commonwealth of Massachusetts, have invented a new and useful Improvement in Insulating Handle Connections, of which the following is a full specification, reference being made to the accompanying drawings, wherein—

10 Figure 1 shows a portion of a teapot or similar article with a handle embodying my invention, showing the upper joint in section. Fig. 2 is a modified form of my improved insulating handle connection. Fig. 3 is a sectional detail of my connection. Fig. 4 is a sectional detail of the modification of my connection.

15 My invention relates to an insulating handle connection for handles of vessels containing hot liquids to prevent the conduction of heat from the vessel to its handle; and it consists of a joint having an invisible insulating washer against which the two ends of the handle are clamped. One of the ends is provided 20 with a cup-shaped end which incloses the insulating-washer and a portion of the end in order to conceal and protect the said washer, and the two ends are axially joined by a bolt or pin, as is hereinafter described in detail.

25 Referring to the drawings, A is the vessel, and B the handle, *a a* and *b b* being the ends of the handle on each side of the insulation.

30 C is my insulating-washer, which I preferably make of cork, and D is the cup-shaped end piece, which is preferably soldered to the end *b* of the handle B. This end piece D is perforated at its center and has at its center the tube *d*, which projects back into the handle B and is threaded in order to engage with 35 the bolt E, which joins the two ends *a* and *b*. As shown in Fig. 1, the end *a* of the handle is closed except for a central perforation, through which the bolt E passes, its head *e* being inside of the end *a*, and between the 40 head *e* of the bolt and the closed end *a* of the handle I place the second insulating-washer F, also, preferably, of cork. When the bolt E is passed through the washer F, end *a*, washer C, and is screwed tightly into the tube 45 *d*, which is joined to the end *b*, as hereinbefore described, it will be seen that the two ends of the handle *a* and *b* are rigidly joined

and at the same time perfectly insulated, as there is no metallic connection, the two ends being simply clamped tightly together against the insulating-washer C. The edges *d* of the cup-piece D are made to project slightly over the end *a* of the handle, but do not touch the metal, a slight air-space being left between, as shown in Fig. 1. Thus a joint is produced 55 which presents the appearance of an ornamental ring about the handle, as shown in the lower joint in Fig. 1, but which is in reality a perfectly, although invisibly, insulated joint, as hereinbefore described. 60

65 After my joint has been made as described and the ends *a* and *b* joined it is necessary to attach the ends *a a* to the vessel, which is usually done by soldering. With metals which are poor conductors of heat, such as white-metal, the heat required for this soldering does not reach the cork washers C and F sufficiently to injure them at all; but when the metal used is silver or other good conductor of heat it is found that in the process of soldering the cork in the washers is badly burned, 70 so that the joint is ruined. In order to obviate this difficulty, I adopt, when necessary, the modified form shown in Figs. 2 and 4, which embodies the same elements as the first 75 form of joint described—to wit, the centrally-perforated cup-shaped end piece D', secured to the end *b'*, as before, the centrally-perforated end *a'*, the cork washer C', and the connecting-pin E'. This joint also presents the 80 same appearance as the first one described, but possesses the advantage that it can be connected after the soldering is all done, and hence the cork washer is not injured. My 85 connecting-pin E' is soldered or otherwise 90 metallically secured to the end *a'*, which is then soldered to the vessel A'. The pin E' is then passed through the cork washer C' and central perforation in the end piece D', which has been previously soldered to the end *b'*, 95 and a transverse pin or joint P is then passed through the end *b'* of the handle and end of pin E', thus clamping the ends *a'* and *b'* together, as before, against the washer C'. 100

What I claim is—

1. In an insulated handle the combination of the members secured to the vessel, the handle proper, the insulated section and means for securing the parts together, said insulated

section having a cup-shaped chamber and carrying the insulating material, the chambered section concealing the insulating material and arranged out of contact with one of the members of the handle, substantially as described.

5 2. In an insulated handle, the combination of the members secured to the vessel, the handle proper, the insulated section and means for securing the parts together, the said insulated section having a cup-shaped chamber and carrying the insulating material, the

chambered section concealing the insulating material, and arranged out of contact with one of the members of the handle, and an insulated washer F, for insulating the securing means, substantially as described.

15 In witness whereof I have hereunto set my hand.

WILLIAM McAUSLAND.
